TRAVERSE MECHANISM FOR WINDING MACHINES

Ernest R. Swanson, Cranston, R. I., assignor to Universal Winding Company, Boston, Mass., a corporation of Massachusetts

Application November 7, 1939, Serial No. 303,276

15 Claims. (Cl. 242—31)

This invention relates to winding machines, and particularly to machines for winding filling bobbins, cops, pirns and similar packages of yarn for use in loom-shuttles or for other purposes such as supplies for further transfer processes. By the term "bobbin" or "cop" as herein-after used in the present specification and claims is meant any wound mass of strand material, either textile or otherwise, built up in overlapping layers with the package growing by longitudinal or axial extension; and the term "yarn" as herein-after employed is intended to apply to all kinds of strand materials.

In machines of the present type it has been the usual practice to employ a reciprocating thread-guide for traversing the strand to an extent less than the full length of the package and by gradually advancing the guide to dispose the yarn in conical chases whereof to build the bobbin of cylindrical form with a tapered end. The conventional method of feeding the strand-guide along the length of the package consists in the use of a screw-threaded traverse-rod on which the guide is mounted with a nut engaging the threads on the rod and arranged to be rotated intermittently by a contact-member or progression-wheel contacting with the periphery of the wound mass at each rearward reciprocation of the rod. With this well known type of traversing means the contact-wheel must engage frictionally with the rotating bobbin to be turned thereby and it has been found in some instances, particularly in winding fine yarns such as rayon and other synthetic materials, that the contact of the progression-wheel with the bobbin has a deleterious effect on the yarn. Stated briefly, the frictional engagement of the contact-wheel with the surface of the winding causes an abrading action which roughens the fibers or otherwise damages the material so that defects may appear in the fabric or other product in which the yarn is eventually incorporated.

To avoid any such injurious action by the contact of a progression-wheel with the yarn on the winding package the present invention has for one of its objects to provide means for advancing the strand-guide along the traverse-rod without the use of such contact means.

Another object of the invention is to provide means for advancing the strand-guide along the traverse-rod adapted to be actuated intermittently by the reciprocatory motion of the rod.

Another object of the invention is to provide a traversing mechanism of the type indicated in which means connected to the guide engage the

screw-threads on the traverse-rod and the rod is intermittently rotated to feed the engaging means and thereby advance the guide longitudinally of the rod.

Another object of the invention is to provide a traversing mechanism of the type indicated comprising ratchet-means actuated by the reciprocatory motion of the traverse-rod to turn the latter to advance the guide therealong.

Another object of the invention is to provide a traversing mechanism of the type indicated having means for adjusting the ratchet-means to regulate the extent of turning motion of the traverse-rod within fine limits.

Another object of the invention is to provide an improved traversing mechanism which may be applied to standard types of machines by substituting it for certain parts thereof without change in the general construction of the machine.

Further objects of the invention are set forth in the following specification which describes a preferred form of construction of the improved traversing means, by way of example, as illustrated by the accompanying drawings.

In the drawings:

Fig. 1 is an elevational side view of one unit of a multi-spindle winding machine showing the main frame or casing of the machine in section to illustrate the driving means for the winding spindle and the reciprocating means for the traverse-rod;

Fig. 2 is an enlarged plan view showing the relation of the present improved traversing means to the winding spindle;

Fig. 3 is an enlarged elevational view of the traversing means and the ratchet-mechanism for intermittently rotating the traverse-rod with certain of the parts shown in section;

Fig. 4 is a detailed view of the end bearing for the traverse-rod showing the means by which it is keyed to the ratchet-wheel and arranged to slide in a sleeve rotatable in the end bearing;

Fig. 5 is a side view of the strand-guide showing the means for connecting it with the screw-threads of the traverse-rod;

Fig. 6 is a part-sectional side view of the ratchet-mechanism for rotating the traverse-rod; and

Fig. 7 is a similar view showing the rocker-arm carrying the pawls for the ratchet in a different position from that illustrated in Fig. 6.

The present invention is herein illustrated and described as applied to a winding machine of a

type similar to that disclosed in United States Letters Patent No. 946,831 granted January 18, 1910, to Simon W. Wardwell. In general, the machine comprises a frame or casing 2 mounted on legs or standards 3, as indicated in Fig. 1 of the present drawings, and arranged with a plurality of winding spindles 5 projecting from the side of the casing. Only one of the winding spindles is herein shown as being journaled in bearings 6 and 7 at opposite sides of the casing 2 and driven from a horizontal shaft 8 journaled therebelow with helical gears 9 and 10 connecting the drive. A second drive-shaft 15 carries a helical gear 16 meshing with a gear 17 free to rotate on the spindle 5, the gear 10 being connected to drive the spindle through a clutch 20 and the gear 17 being similarly connected to drive a cylindrical cam 21 which is free to rotate on the spindle 5.

20 A horizontal traverse-rod 25 is mounted to slide longitudinally in a bearing 24 on the side of the frame 2, its rearward end being connected by a link 27 to a rocker-arm 28 mounted fast on a rock-shaft 29 extending horizontally of the frame 2. The upper end of the rocker-arm 28 carries a roller or bowl 30 engaging a helical groove 31 in the cam 21, by means of which the arm is oscillated during the rotation of the cam. The inner end of the link 27 may be connected to the rocker-arm 28 by a pin 32 engaging in any one of a series of holes 33 in the arm whereby the traverse-rod 25 is caused to be reciprocated from the oscillation of the arm and its extent of reciprocation may be adjusted 35 in accordance with requirements.

The traverse-rod 25 is constructed in two axially-aligned sections with its outer section 26 formed with helical screw-threads as shown most clearly in Figs. 1 and 2. The inner end of the screw-threaded section 26 projects through a bore in a thimble-like sleeve 35 with the extremity of the rod reduced in diameter and riveted through a collar 36. The sleeve 35 is counterbored at 37 to receive the collar 36 and 40 a bushing 38 in the bore surrounds the outer end of the main section of the traverse-rod 25 with a tapered pin 39 securing the sleeve and bushing thereto. By means of this construction the outer threaded section 26 of the traverse-rod 50 is connected in alignment with the main section 25 to be reciprocated therewith while permitting the section 26 to rotate with respect to the main section 25.

The outermost end of the threaded section 26 of the traverse-rod is mounted to slide in a sleeve 40 which is journaled in an outboard bearing 44 formed as a part of a bracket 45. The bracket 45 is attached to the outer end of a horizontal arm or bracket 46 fastened to the side of the main frame 2, see Figs. 1 and 3. Referring particularly to Fig. 4 of the drawings, the inner end of the sleeve 40 is reduced in diameter and screw-threaded at 47 to receive a disk or wheel 50 formed with ratchet-teeth 51 on its periphery. 60 The ratchet-wheel 50 abuts a shoulder on the end of the sleeve 40 and cooperates with a head or enlargement 48 at the opposite end of the sleeve to restrain the sleeve from longitudinal movement in its bearing 44. A spline or keyway 70 52 formed in the side of the traverse-rod section 26 is engaged by a key 53 provided with projections 54 and 55 at its end engaging radial holes in the bore of the sleeve 40. By means of this construction the traverse-rod section 26 is keyed 75 to turn with the sleeve 40 and ratchet-wheel 50

while being slidable longitudinally through the bore of the sleeve to accommodate its reciprocating motion.

The ratchet-wheel 50 is arranged to be turned intermittently to rotate the traverse-rod section 26 through the means of pawls carried by a rocker-arm 58, to be described later. It will be noted by reference to Fig. 2 that the traverse-rod section 26 extends opposite to and parallel with the axis of the winding spindle 5 on which the package is wound. The winding spindle 5 may be of any preferred form and, as herein shown, it is provided with a tapered extension for receiving the tubular barrel of a wooden bobbin or yarn-receiver b on which the cop or 10 bobbin B, represented by dot-and-dash lines, is wound.

The strand-guide 4 which is mounted on the threaded section 26 of the traverse-rod is generally of conventional form as comprising a bifurcated arm 60 having the ends of its bifurcations or legs connected to sleeves 61 which are slidably mounted on the rod. Mounted between the ends of the sleeves 61 is a longer sleeve 65, also free to slide on the rod-section 26 and formed with a radial flange 66, see Fig. 3. Connected to the side of the flange 66 is an elbow-shaped member 67 held rotatively therewith by means of a pin or pivot 68. The member 67 is formed with a laterally-projecting arm or right-angle extension 69 through which is threaded a stud 70 carrying a check-nut 71. The stud 70 is also threaded through a lateral extension or flange 72 at the upper end of an arm 73 forming part of a bifurcated element 75. The arm 73 has its counterpart in an opposite arm 74 forming a fork therewith, the ends of both arms being provided with holes for receiving the threaded rod-extension 26 which forms a support for the element. The lower end of the fork of the element 75 is provided with an extension formed into a hook 76 looped around a horizontal rod 77 extending parallel with the rod-section 26 and arranged therebelow with its ends supported in bearings at the inner and outer end of the bracket 46. By this form of construction of the correlated parts described above the element 75 is prevented from turning on the traverse-rod extension 26 while being free to slide therealong; and the member 67 being connected to said element by the stud 70 is also held from turning on the rod. The sleeve 65 is likewise prevented from turning on the rod-extension 26 through its connection with the member 67 by means of the pin or rivet 68.

Referring to Figs. 2 and 5 of the drawings, a lever 80 is pivoted to the side of the member 67 by means of a stud 81 with its forward portion extending through the narrow opening between the flange 66 and member 67 and also through a slot in the sleeve 65; the bottom edge of the lever being shaped to partially encircle the rod-extension 26 and engage in the square-cut threads thereon. A helical spring 82 anchored to a lug 83 on the member 67 has its opposite end connected to an upper arm 84 of the lever 80 whereby to normally maintain the lever in engagement with the threads on the rod-section 26. The rearward arm 85 of the lever 80 is formed with a finger-piece 86 arranged opposite to a similar finger-piece 87 on the member 67, this arrangement providing for manually operating the lever 80 in the manner of shears by pressing the fingers on the two finger-pieces 86 and 87 to lift the forward portion of the lever to free 75

it from engagement with the screw-threads on the rod-extension 26. This manual release of the lever 80 from the screw-threads is provided for the purpose of returning the strand-guide 4 to first position to start winding a fresh package by sliding it rearwardly of the rod-extension 26.

The strand-guide 4 may be of usual construction in the form of a grooved porcelain element fastened to the guide-arm 60 by a screw 62, the strand of yarn or thread y being adapted to lead downwardly through the groove in the guide in the manner indicated by dot-and-dash lines in Fig. 5 to cause it to be wound onto the bobbin B which rotates in the direction indicated by the arrow in this view. In order to restrain the strand-guide 4 from rubbing against the package as it reciprocates to and fro in association therewith the stud 70 is arranged to bear against the rearward tail-portion 78 of the guide-arm 60 as shown in Figs. 1 and 3; the stud being adjustable to position the guide in close relation to, but slightly spaced from, the periphery of the bobbin B.

The ratchet-mechanism for turning the transverse-rod extension 26 comprises the rocker-arm or lever 58, previously referred to, which is connected by a hook-ended rod or link 88 to an actuating lever 90. The actuating lever 90 is pivoted on a stud or pin 91 passing through a bearing in an arm 92 extending horizontally inward from the bracket 45, previously referred to as fastened to the end of the bracket 46. The actuating lever 90 is of bifurcated shape, as shown in Fig. 2 of the drawings, having a forward arm 93 formed with a hole at its end into which the hooked end of the link 88 is engaged, and an opposite parallel arm 95 projecting upwardly with its terminal portion located adjacent the side of the traverse-rod extension 26. The upper extremity of the arm 95 is inclined to the left as viewed in Fig. 3, and formed with an arcuate edge 96 adapted to be engaged by the side of a collar 100 fixed to the traverse-rod section 26, this engagement being for the purpose of rocking the lever 90 to actuate the rocker-arm 58. The collar 100 may be split to adapt it to be clamped on the rod-section 26 by means of a binder-screw 101, thereby providing for its adjustment longitudinally of the rod to regulate the extent of its contact with the actuating lever 90. The actuating lever 90 is normally maintained in the position indicated by full lines in Fig. 3 by means of a helical spring 102 connected to its arm 93 and suspended from the upper bent end of a rod 103. The lower end of the rod 103 is screwed into the supporting arm 92 and held fast by a check-nut 104. A stud 105 threaded through a lug 106 on the under side of the arm 92 is arranged with its end engaging a downwardly-extending finger 107 on the actuating lever 90, whereby to limit the rocking motion of the lever under the action of the spring 102. By turning the stud 105 the position of the arm 95 may be adjusted in relation to the stroke of the collar 100 on the rod-extension 26, thereby providing a relatively fine adjustment for regulating the extent of rocking motion of the lever 90 under the action of the collar for a purpose as later explained more fully. A check-nut 108 on the stud 105 may be set up against the side of the lug 106 to maintain the stud in its adjusted position. A second helical spring 109 hooked through the outer extremity of the arm 93 of the lever 90 is connected at its upper end to the pawl-carrying arm 58 whereby

to prevent lost motion or play of the link 88 in its connection with the arm 58 and the lever 90.

As shown most clearly in Fig. 2 of the present drawings, the ratchet-operating arm or lever 58 carries two pawls 110 and 111 arranged side by side and pivoted on a stud 112 fastened to the side of the arm. The pawls 110 and 111 have pointed toes adapted to engage with the teeth 51 on the ratchet-wheel 50, a bifurcated leaf-spring 113 being provided to act against the pawls. The spring 113 is fastened to an elbow-shaped plate 114 secured to the side of the arm 58 by a nut 115 on the stud 112. The spring 113 has its rearward portion riveted to the laterally-extending portion of the plate 114 with its two fingers extending forwardly to bear against the top of the two pawls 110 and 111. It will be noted by reference to Figs. 2 and 6 that the pointed toe of the pawl 110 is positioned slightly to the rear on the toe of the pawl 111 or, in other words, the pawl 110 is slightly shorter than the pawl 111, the difference in length being equal to half the length of a tooth on the ratchet-wheel. The purpose of this form of construction is to provide that the ratchet-mechanism may be adjusted with extreme accuracy and fineness to vary the turning motion of the ratchet-wheel 50, for example by the distance of one-half of one tooth on its periphery; it being understood that when the arm 95 of the lever 90 is struck by the collar 100 the lever will be rocked to draw the arm 58 downwardly to carry the pawls rearwardly into position to engage one or another tooth on the ratchet-wheel as indicated in Figs. 6 and 7 of the drawings. This action takes place during the forward reciprocatory motion of the rod-section 26, but when the rod reaches the outward extreme of its reciprocation and moves back in the opposite direction the arm 95 of the lever 90 will be released, whereby the spring 102 will rock the lever to cause the link 88 to raise the arm 58. This upward oscillation of the arm 58 then causes the pawls, one or the other of them in accordance with which one is engaged with a tooth on the ratchet-wheel 50, to turn the wheel in a clockwise direction as viewed in Figs. 6 and 7.

In order that under the rapid oscillation of the arm 58 in turning the rod-section 26 the momentum of the rod and its connected sleeve 40 may not cause the parts to rotate beyond the required extent, means are provided for frictionally braking the movement of the sleeve 40. Referring to Fig. 3, a friction disk 116 is held in a bore in the bearing 44 with a helical spring 117 tending to press it against the periphery of the sleeve 40. A screw 118 threaded into the upper end of the bore maintains the spring 117 under compression and may be adjusted to regulate the friction of the disk on the sleeve 40, a check-nut 119 being provided on the screw 118 to secure the latter in its adjusted position.

The construction and arrangement of the traverse-mechanism of the winding machine having been described in detail, its method of operation is explained as follows: At the start of the winding the thread-guide 4 is placed at the inner end of the traverse-rod section 26 by pressing on the finger-pieces 86 and 87 to release the forward end of the lever 80 from the threads on the rod and sliding the guide-arm 60 rearwardly along the latter. To prepare the machine for operation a bobbin b or other yarn-receiver is placed on the spindle 5 and the end of the strand of yarn y leading from a suitable source of supply is attached to the receiver in any con-

venient manner after leading it through the groove in the strand-guide 4.

The machine is started to operate by rocking the rod 17 to clutch the gear 10 with the spindle 5 and the gear 17 with the cam 21 in accordance with the arrangement shown in the patent referred to previously; it being understood that the shafts 8 and 18 for driving these last-named gears are rotated continuously from a suitable source of power. As the spindle 5 is rotated the yarn will be wound onto the bobbin b and the cam 21 will actuate the rocker-arm 28 to reciprocate the traverse-rod 25 and its connected section 26 longitudinally of the winding spindle. It will be understood that the extent of reciprocation of the traverse-rod 25, and thereby the thread-guide 4 carried on the rod-extension 26, is equal to only a fraction of the full length of the bobbin to be wound and consequently the yarn will be deposited on the bobbin b in relatively short layers. Each time the traverse-rod section 26 moves outwardly away from the frame 2 the collar 100 will ride against the curved end 96 of the lever 90 to rock the latter in a clockwise direction as viewed in Figs. 1 and 3. This rocking motion of the lever 90, indicated by the full and dash lines in Fig. 3, will cause its arm 93 to draw down the pawl-arm 58 which is connected thereto by means of the link 88, see Fig. 7. The pawls 110 and 111 are thereby retracted over the teeth 51 of the ratchet-wheel 50 and after the collar 100 reaches the outward end of its reciprocatory motion with the rod-section 26 it will recede from the lever 90 allowing the latter to be rocked back in the opposite direction under the tension of the spring 102. This rearward rocking motion of the lever 90 will cause its arm 93 to raise the link 88 and thereby rock the arm 58 in a clockwise direction as viewed in Figs. 6 and 7. Therefore, since one or the other of the pawls 110 and 111 will be in engagement with a tooth on the ratchet-wheel 50 the latter will be rotated through a part of a revolution to turn the traverse-rod section 26 with it by means of its key connection at 53 with the sleeve 40, see Fig. 4.

The turning motion thus imparted to the traverse-rod section 26 will cause its threads to act through the lever 80 engaged therewith to advance the arm 60 and strand-guide 4 a certain distance outwardly along the rod. The extent of this advance or feed of the thread-guide is usually equal to about the thickness of a strand of yarn and may be regulated by adjusting the collar 100 on the rod section 26; a finer adjustment being secured by turning the stud 105 to locate the lever 90 in such position as to control the extent of its movement under the action of the collar 100.

The winding proceeds in this manner with the strand-guide 4 depositing the yarn in relatively short layers or courses which build up in conical formation as indicated by the dot-and-dash lines in Figs. 2 and 3. Each time the threaded rod-section 26 is rotated the strand-guide 4 will be advanced to step the next-wound layer in advance of a precedingly-laid course of the yarn and in this way the bobbin grows by longitudinal extension until the guide 4 has been fed outwardly along the traverse-rod section 26 to a point adjacent the end of the bobbin b. At this juncture suitable stop-motion devices, not herein shown or described, come into action to arrest the operation of the machine by declutching the gears 10 and 17 to permit them to idle. It has been stated that as the traverse-rod section 26 is intermittently rotated frictional resistance to

the turning of the sleeve 40 connected therewith, under the braking action of the disk 116 and spring 117, prevents overrunning of the rod and thus the advance or feed of the strand-guide 4 is maintained constant within prescribed limits. The present improved traversing mechanism thus operates to produce accurately formed bobbins or packages with the yarn laid in even courses, and without imposing any injurious action on the yarn by a progression-wheel or contact-member. Consequently, the finest and most delicate materials may be wound successfully without abrading or injuring the fibers.

It will be observed further that the present invention provides a novel and simple mechanism for eliminating the contact-means or progression-wheel usually considered necessary for use in machines of the present type. While the improved mechanism is herein illustrated in a preferred form of construction, it is to be understood that various modifications may be made in the structure and arrangement of its parts without departing from the spirit or scope of the invention. Therefore, without limiting myself in this respect, I claim:

1. In a winding machine, means for rotating a package, a screw-threaded traverse-rod extending longitudinally of the package, means for effecting relative reciprocation between the package and traverse-rod, a strand-guide slidable longitudinally of the traverse-rod, means connecting the strand-guide with the threads on the rod, and means actuated by the relative reciprocatory movement of the package and traverse-rod for intermittently rotating the rod to feed the strand-guide therealong to advance the layers of winding 35 of the package.

2. In a winding machine, means for rotating a package, a screw-threaded traverse-rod extending longitudinally of the package, means for reciprocating the traverse-rod, a strand-guide slidable on said traverse-rod, means connecting said strand-guide with the screw-threads on the rod, and means actuated by the reciprocating traverse-rod for rotating it intermittently to feed the guide therealong during its reciprocation.

3. In a winding machine, means for rotating a package, a screw-threaded traverse-rod extending longitudinally of the package, means for effecting relative reciprocation between the package and traverse-rod, a strand-guide slidable longitudinally of the traverse-rod, means connecting said guide with the screw-threads on the rod, and means actuated by the reciprocating means during a portion of its movement to rotate the traverse-rod to feed the strand-guide therealong.

4. In a winding machine, means for rotating a package, a screw-threaded traverse-rod extending longitudinally of the package, means for effecting relative reciprocation between the package and traverse-rod, a strand-guide slidable longitudinally of the traverse-rod, means connecting the strand-guide with the screw-threads on the rod, and ratchet-means actuated by the reciprocating means during a portion of its movement for rotating the traverse-rod to feed the strand-guide therealong.

5. In a winding machine, means for rotating a package, a traverse-rod formed with helical threads on its periphery, means for effecting relative reciprocation between the traverse-rod and package, a strand-guide slidable longitudinally of the traverse-rod, means connecting the strand-guide with the screw-threads on the rod, ratchet- 70 means actuated by the reciprocating means during a portion of its movement for rotating the traverse-rod to feed the strand-guide with the screw-threads on the rod, ratchet- 75

means for rotating the rod, and means actuated by the reciprocating means to operate the ratchet-means.

6. In a winding machine, means for rotating a package, a traverse-rod formed with helical screw-threads, means for effecting relative reciprocation between the traverse-rod and package, a strand-guide slidable longitudinally of the package, means connecting the strand-guide with the threads on the traverse-rod, a ratchet-wheel for rotating the traverse-rod, a lever for actuating the ratchet-wheel, and means operated from the reciprocating means to actuate the lever to turn the ratchet-wheel to rotate the rod to feed the strand-guide therealong.

7. In a winding machine, the combination of means for rotating a package, a traverse-rod formed with helical screw-threads, means for reciprocating the traverse-rod longitudinally of the package, a strand-guide slidable longitudinally of the traverse-rod, means connecting the strand-guide with the threads on the rod, ratchet-means for rotating the traverse-rod, a lever for actuating the ratchet-means, and means on the traverse-rod engageable with the lever to actuate the latter and operate the ratchet-means to turn the rod.

8. In a winding machine, means for rotating a package, a screw-threaded traverse-rod extending longitudinally of the package, means for reciprocating said traverse-rod, a strand-guide mounted on the traverse-rod to slide longitudinally thereof, means connecting said strand-guide with the screw-threads on the rod, a ratchet-wheel for turning the rod, a rockable lever, a pawl carried by the lever for turning the ratchet-wheel, and means on the traverse-rod engageable with the lever to rock the latter to cause the pawl to turn the ratchet-wheel to rotate the rod.

9. In a winding machine, means for rotating a package, a traverse-rod reciprocable longitudinally of the package, said rod comprising axially-aligned connected sections with one section formed with screw-threads on its periphery, said screw-threaded section connected to the main section of the rod for rotation relative thereto, a strand-guide slidable on the screw-threaded section of the rod, means connecting said strand-guide with the threads on the rod, means for reciprocating the traverse-rod, and means for rotating the screw-threaded section of the traverse-rod relative to its main section during its reciprocation to feed the strand-guide longitudinally thereof.

10. In a winding machine, means for rotating a package, a screw-threaded traverse-rod extending longitudinally of the package, means for reciprocating said rod, a ratchet-wheel connected to rotate the rod, a rockable lever, a pawl on said lever for turning the ratchet-wheel, and an abutment adjustable longitudinally of the traverse-rod and adapted to engage the lever to rock the latter to turn the ratchet-wheel to rotate the rod.

11. In a winding machine, means for rotating a package, a screw-threaded traverse-rod ex-

tending longitudinally of the package, means for reciprocating said traverse-rod, a strand-guide slidable longitudinally of the traverse-rod, means connecting said strand-guide with the screw-threads on the rod, ratchet-means for rotating the traverse-rod, a lever for actuating said ratchet-means, means on the traverse-rod engageable with the lever to rock the latter at each reciprocation of the rod, and means for adjusting the normal position of the lever to regulate its extent of movement under the action of the engaging means on the traverse-rod.

12. In a winding machine, means for rotating a package, a screw-threaded traverse-rod extending longitudinally of the package, means for reciprocating said traverse-rod, a strand-guide slidable longitudinally of the rod, means connecting the strand-guide with the threads on the rod, a ratchet-wheel for rotating the rod, a rockable lever, a pair of pawls carried by said lever, one of said pawls being of less length than the other pawl to vary their engagement with the teeth on the ratchet-wheel, and means for rocking the lever to cause the pawls to turn the ratchet-wheel to rotate the traverse-rod to feed the thread-guide therealong.

13. In a winding machine, the combination of a winding spindle, a screw-threaded traverse-rod reciprocable longitudinally of the winding spindle, a sleeve for slidably supporting the end of the traverse-rod, a ratchet-wheel connected to rotate the sleeve, means for rotating the ratchet-wheel, a strand-guide slidable longitudinally of the traverse-rod, and means connecting said guide with the threads on the rod whereby the rotation of the latter acts to feed the guide along the rod.

14. In a winding machine, a frame, a winding spindle journaled in said frame, a traverse-rod reciprocable in a bearing on said frame, means to reciprocate said rod, a screw-threaded rod arranged coaxially of the traverse-rod and rotatively connected therewith to be reciprocated thereby, a strand-guide slidable along the threaded rod, means connecting the strand-guide with the threads on the rod, a bearing supported from the frame to slidably support the outer end of the traverse-rod, a ratchet-wheel supported from the bearing with the threaded rod slidable through its bore, means for keying the ratchet-wheel to turn the rod, and means for turning the ratchet-wheel to rotate the threaded rod during its reciprocatory motion to feed the strand-guide therealong.

15. In a winding machine, means for rotating a package, a screw-threaded traverse-rod reciprocable longitudinally of the package, means for reciprocating said traverse-rod, a strand-guide slidable longitudinally of the rod, means connecting said strand-guide with the threads on said rod, means for rotating the traverse-rod to feed the thread-guide longitudinally thereof, and friction means for preventing overrunning of the rod during its rotation.
